UNITED STATES PATENT OFFICE.

ANDREWS MOUCHIN, OF MOSCOW, RUSSIA.

FEED-WATER PURIFIER FOR BOILERS.

1,047,829.

Specification of Letters Patent.

Patented Dec. 17, 1912.

Application filed December 27, 1910. Serial No. 599,601.

To all whom it may concern:

Be it known that I, ANDREWS MOUCHIN, a subject of the Czar of Russia, residing at House of Education, Moscow, Russia, have invented certain new and useful Improvements in Feed-Water Purifiers for Boilers; and I do hereby declare the following to be a full, clear, and exact description of the invention, such as will enable others skilled 10 in the art to which it appertains to make and use the same.

This invention relates to means of purifying feed water for locomotive and other boilers, and has for its object to provide 15 settling chambers for receiving the sediment of the water entering the boiler, and the removal of the sediment from the settling chambers.

With the above and other objects in view 20 as will appear, the invention consists in certain combinations and arrangements of the parts hereinafter described, and the novel features thereof will be particularly pointed out in the appended claims.

25 To fully understand the invention, reference will be had to the accompanying drawings illustrating the preferred embodiment thereof, and in which like characters of reference indicate corresponding parts.

30 Figure 1 is a longitudinal view, partially in section, of a locomotive boiler embodying my invention, and Fig. 2 is a transverse sectional view taken on line 2—2 of Fig. 1.

In the drawings, 1 represents a locomotive 35 boiler of ordinary construction, and 2 the tubes. To either side of the tubes 2 is located a vertically disposed plate 3, which plates are secured at one end to a vertical back wall 5 that extends from side to side of 40 the boiler just in front of the fire box wall. Extending from the back wall 5, and arranged in spaced relation between each vertical side plate 3 and the shell of the boiler are vertical partitions 6 of less height than 45 the vertical plates 3, and forming settling chambers 7 for receiving the sediment from the water. Connected to the upper ends of the vertical plates 3 and extending longitudinally to the back wall 5, are outwardly 50 inclined guide-plates 8 having curved lower ends which terminate below the top of the vertical partitions 6 and project into the settling chambers 7. Extending the full length, near the bottom, of each settling

chamber 7, and projecting through the front 55 end of the boiler is a pipe 9 which is provided with apertures 10 through which the sediment may pass. The pipes 9 are connected centrally by a pipe-yoke 11 in which are arranged shut-off valves 12, and from 60 the pipe-yoke leads a pipe 13 which may be connected to a steam supply for blowing out the settling chambers. The pipe 13 is also provided with a shut-off valve 14. The projecting ends of the pipes 9 are closed by 65 plugs 15.

From the foregoing it is apparent that when water is admitted to the boiler, it is directed to the settling chambers by the guide-plates and the sediment or heavy particles settle to the bottom, while the clear water is allowed to flow over the vertical partitions and into the casing around the sides and top of the boiler tubes. The spaces between the walls 1, 3, 6 and 8 provide 70 channels or passageways forming a circuitous course through which the water flows, as 75 will be understood.

Although the elements set forth and herein described are fully adapted to accomplish 80 the purposes for which they are intended, it is to be understood that various changes in the form, proportion and minor details of construction may be resorted to without departing from or sacrificing any of the ad- 85 vantages of the invention.

Having fully described my invention, what I claim is:—

1. In a means for purifying feed water for tubular boilers, the combination of plates 90 disposed adjacent the sides of the tubes, a vertical partition arranged between each of said side plates and the boiler forming settling chambers, a curved plate connected to each of said side plates and extending below 95 the top of the partition, and means for cleaning the settling chambers, substantially as described.

2. In a means for purifying feed water for tubular boilers, the combination of plates 100 disposed adjacent the sides of the tubes, a vertical partition arranged between each of said side plates and the boiler forming settling chambers, a curved plate connected to each of said side plates and extending below 105 the top of said partition, a pipe arranged in the bottom of each settling chamber and projecting through the front end of the

boiler, removable plugs in the projecting ends of the pipes, a pipe-yoke connecting said pipes, valves in the pipe-yoke, and suitable means for connecting the pipe yoke to a source of pressure for removing the sediment from the settling chambers, substantially as described.

In testimony whereof, I affix my signature, in presence of two witnesses.

ANDREWS MOUCHIN.
